UNITED STATES PATENT OFFICE.

HORATIO G. H. REED AND JERRY DONOHUE, OF MILWAUKEE, WISCONSIN.

RAILROAD-TRACK FLANGER AND SNOW-PLOW.

SPECIFICATION forming part of Letters Patent No. 328,718, dated October 20, 1835.

Application filed August 17, 1835. Serial No. 174,572. (No model.)

To all whom it may concern:

Be it known that we, HORATIO G. H. REED and JERRY DONOHUE, both of Milwaukee, in the county of Milwaukee, and in the State of 5 Wisconsin, have invented certain new and useful Improvements in Railroad-Track Flangers and Snow-Plows; and we do hereby declare that the following is a full, clear, and exact description thereof.

10 Our invention relates to devices for removing snow from railroad-tracks, and especially from about the flanges of the rails thereof; and it consists of certain peculiarities of construction, as will be fully set forth hereinafter.

15 In the drawings, Figure 1 is a side elevation of our device. Fig. 2 is a plan view of the same with the floor or bottom of the car removed; and Fig. 3 is a front elevation, partly in section.

20 Our device is shown as being suspended from the floor-timbers and between the wheel-trucks of an ordinary box-car, only so much of which is shown as is necessary to illustrate the invention, the floor of the car being shown 25 at A, strengthened on its under side by the timbers a a, &c., which are supported in the ordinary manner upon the trucks. (Not shown.)

20 Our device is shown as being suspended from the floor A by means of suitable bolts, and is located about midway between the front and rear trucks a slight distance above the track. This base-board (which may be of wood or metal, or both) is 35 of considerable thickness, and its front edge is beveled off or inclined, as shown at b.

C is a rack-bar secured to the upper side of the floor A, and D is a lever having an ordinary spring-catch, d, for engagement with the 40 notches c in the rack C at any point desired. The lever D is secured at d' to the base-board B, and near its attached end carries a link, E, the lower end of which is pivoted to the cutter-blade F. An angle-plate, f, is bolted to the rear edge of the foundation F' of the blade F, and one flange of this plate rests on the beveled front edge of the base-board B when the lever D is at its forward limit, as shown 45 in full lines in Fig. 1, and the blade F is kept down to place when in use by means of a spring, e, on the link E. The blade F is connected by two straps or braces, G G, to the

timbers a' a' of the floor A, and back of this point of attachment each of said timbers is perforated to receive a rod, h, carrying a link, 55 g, whose lower end is pivoted to the brace G, while above the timber a' the rod h passes through a double spring, H, whose tension is regulated by the hand-screw h'.

By means of the spring e, should the blade 60 meet with a block of ice or other obstruction below the level of the rail, it would lift up and pass over it on either side of the track without injury.

The springs H H are to counterbalance the 65 weight of the blade, so as to enable it to be more easily raised by the lever D.

The said blade F is made in sections, forming a series of steel knives or cutting-plates, f' f', which are bolted or otherwise secured to 70 a foundation, F', so that the front edges of each section shall form a continuous cutting-edge projecting below and beyond the front edge of the said foundation, both edges extending in the same curved line, as shown in Fig. 2, where 75 the dotted line f'' f'' indicates the front edge of the said foundation, which, furthermore, is hollowed out on its under surface to receive and embrace the tread of the rails, and is bent or curved down on each side of each rail, so 80 as to form a sort of saddle, as shown at F' in Fig. 1.

A great advantage of making the cutting-blade in sections lies in the fact that should one section f' become broken or injured it 85 could be removed and replaced by a new plate without disturbing the rest of the blade F, thereby saving time, labor, and expense.

I I are the rear, and K K' the side, wings or deflectors for guiding the snow off the base-board after it has been received thereon from the cutting-blade in the forward movement of the plow. The rear wings, I I, are stationary and the side wings, K K', movable. In the position of these parts shown in full lines in 95 Fig. 2, the snow will pass off to the right and left of the track, being crowded off by the fresh accumulation of snow as the plow moves forward; but if, for instance, it is desired that the snow shall all pass off to the right of the 100 track, (as on a double-track road,) then the deflector K' is turned to the position shown in dotted lines in said figure, and there made fast, the side wings in either instance being

secured by bolts J, which pass through eyes k at the rear ends of the side wings and are made fast by nuts below the base-board. The other side wing, K, is capable of a similar adjustment if it is desired that the snow shall be thrown to the other side of the track, and the front ends of the side wings are secured in like manner by bolts j j, on which they easily turn.

10 As stated, our device is shown in connection with an ordinary box-car, the sides of which are indicated at a² a² in Fig. 3; but we do not confine ourselves to such an arrangement, inasmuch as our snow-plow and rail-flanger may 15 be mounted upon or suspended from an independent truck-frame or platform and adapted to go before an engine or in any part of a train, as desired.

Under some circumstances the movable 20 wings K K' may be unnecessary, and in such cases they may be dispensed with and the stationary wings I I brought forward just back of the beveled front edge of the base-board and there secured, in which event a base-board of less length would answer the purpose.

Having thus described our invention, what we claim as new, and desire to secure by Letters Patent, is—

30 1. In a device for removing snow from railroad-tracks, the combination of a base-board with beveled or inclined front edge, a cutting-blade, the rear edge of which rests on the beveled edge of the base-board, and a lever 35 for changing the elevation of the cutting-blade, substantially as set forth.

2. In a device for removing snow from railroad-tracks, the combination of a base-board, a cutting-blade, the rear edge of which rests on 40 the base-board, a lever for changing the elevation of the cutting-blade, a link for connecting the lever and cutting-blade, and a spring on the link between the lever and blade, substantially as set forth.

45 3. In a device for removing snow from railroad-tracks, the combination of a base-board, a cutting-blade, the rear edge of which rests

on the base-board, a lever for changing the elevation of the cutting-blade, a link connecting the lever and cutting-blade and carrying 50 a spring intermediate between said parts, and pivoted braces on either side of the lever connecting the cutting-blade with the platform or truck-frame above it, substantially as set forth.

4. In a device for removing snow from railroad-tracks, the combination, with a truck-frame or platform, of a base-board suspended therefrom, a cutting-blade, the rear edge of which rests on the base-board, a lever for changing the elevation of the cutting-blade, a 60 link connecting the lever and cutting-blade and carrying a spring intermediate between said parts, pivoted braces connecting the cutting-blade with the frame or platform above it, rods passing through the said frame or 65 platform having tension-springs secured to their upper ends, and links pivoted to said braces secured to their lower ends, substantially as set forth.

5. In a device for removing snow from railroad-tracks, the combination, with a base-board having an inclined front edge, of a cutting-blade whose rear edge rests on the inclined front edge of the base-board and stationary wings secured to the base-board to 75 deflect the snow therefrom, substantially as set forth.

6. In a device for removing snow from railroad-tracks, the combination, with a base-board and stationary wings secured thereto, of movable side wings adapted to be swung from either side to the center and there secured, whereby the snow may be thrown off on either side of the track, substantially as set forth.

In testimony that we claim the foregoing 85 we have hereunto set our hands, at Milwaukee, in the county of Milwaukee and State of Wisconsin, in the presence of two witnesses.

HORATIO G. H. REED.
JERRY DONOHUE.
